UNITED STATES PATENT OFFICE.

HENRY STURM, OF ARLINGTON, NEW JERSEY.

DESIGN FOR ORNAMENTATION OF FABRICS.

SPECIFICATION forming part of Design No. 21,795, dated August 23, 1892.

Application filed June 21, 1892. Serial No. 437,523. Term of patent 3½ years.

To all whom it may concern:

Be it known that I, HENRY STURM, of Arlington, in the county of Hudson and State of New Jersey, have invented and produced a new and original Design for the Ornamentation of Fabric, of which the following is a specification, reference being had to the accompanying drawing, in which the figure represents a piece of fabric trimming having my new design produced thereon.

The design relates more particularly to embroidered fabric trimming for shirts, including night-shirts; and it consists of the ornamentation shown. Thus *a* indicates a female figure in erect posture and representing with more or less exactness the conventional fig-

ure of Columbia. The figure appears as grasping a sword *b* with one hand, and at the opposite side appears the representation of a gonfalon indicated by the letter *c*, the staff *c'* 20 of which appears as if entered in the ground. One of the points or streamers *c'* of the gonfalon is represented as if partially entwined around the staff, the latter crossing it.

I claim—

The design for the ornamentation of fabric, herein shown and described.

HENRY STURM.
